[57] CLAIM

The ornamental design for an element of a shoe, as shown and described.

DESCRIPTION

FIG. 1 is a side elevational view of an element of a shoe showing my new design;

FIG. 2 is a front elevational view thereof;

FIG. 3 is a rear elevational view thereof; and,

FIG. 4 is a top plan view thereof.

The broken line showing of the remainder of the shoe is for illustrative purposes and forms no part of the claimed design.
